ATTORNEY

UNITED STATES PATENT OFFICE.

HENRY A. STAAB, OF MILWAUKEE, WISCONSIN.

SOAP-FLAKER.

1,314,026.

Specification of Letters Patent. Patented Aug. 26, 1919.

Application filed November 30, 1918. Serial No. 264,829.

To all whom it may concern:

Be it known that I, HENRY A. STAAB, a citizen of the United States, and resident of Milwaukee, in the county of Milwaukee and

5 State of Wisconsin, have invented certain new and useful Improvements in Soap-Flakers; and I do hereby declare that the following is a full, clear, and exact description thereof.

10 My invention relates to new and useful improvements in cutting devices, more particularly of that type including a body plate over which an article to be cut is slid for engagement by blades upstanding from the 15 plate. It is the object of my invention to provide a device of this character which is particularly adapted for cutting bars of soap into ribbons or flakes for laundry purposes, and it is more particularly my object 20 to provide a device of this character whereby the cutting operation may be most conveniently and rapidly carried out.

A further object resides in the provision 25 of a device of this character which may be manufactured in a most economical manner consistent with desired strength and durability and a most efficient discharge of the various functions of its parts.

30 A more detailed object resides in the provision of reinforcing members for the body plate of the device which also serve as guides for the soap or other article to be cut.

A still further object resides in the provision of a device of this character which is 35 formed from a rectangular body blank of metal whereby any wastage of metal in the stamping operation is entirely avoided.

A still further object resides in the provision of an improved blade formation 40 struck from the body plate, whereby hardened edges for the blades are procured incidental to the forming operation.

With the above and other objects and advantages in view, which will be apparent as 45 the description proceeds, my invention resides in the novel features of construction, combination and arrangement of parts as hereinafter more particularly described and defined by the appended claims.

50 In the accompanying drawings:

Figure 1 is a plan view of the body blank from which my improved soap flaker is formed.

Fig. 2 is a plan view of the completed de- 55 vice.

Fig. 3 is a side elevational view thereof.

Fig. 4 is a transverse sectional view there-
through on the line 4—4 of Fig. 2.

Fig. 5 is a detailed view showing the for-
mation of the blade portions. 60

Referring now more particularly to the accompanying drawings, it is noted that the body plate 10 of the device is stamped out in rectangular shape whereby wastage of metal is entirely avoided. The blank is pro-
65 vided adjacent one end with slits *a* each ex-
tending inwardly from its side edge a dis-
tance substantially equal to one quarter of
the width of the blank, and the sides of said
end portion of the blank are bent on fold 70
lines *b* extending longitudinally from the
inner ends of the slits to the extremity of the
blank, thus forming a reduced tongue 11 of
double thickness, the bent portion of the
blank lying at the under surface of the 75
tongue. This tongue is bent downwardly
from the slits *a* and then bent reversely to
form a channel 12 for receiving the edge of
a tub or other support on which it is desired
to rest the device, the extremity of the 80
tongue being directed inwardly at 13 to en-
gage the body of the blank, to which it is
preferably soldered to effect a rigid struc-
ture.

For reinforcing the body plate, and at 85
the same time affording guides for soap or
other work material which is slid thereon,
and for providing a handle for the device,
a length of relatively thick wire is pro-
90 vided which is bent in an elongated U-shape,
the legs 14 of the wire being disposed on
the body plate and secured thereto by roll-
ing the side portions of the body plate
thereabout at 15, while the bight of the 95
wire projects from the end of the body
plate remote from the tongue 11. The end
of the body blank remote from the tongue
11 is provided with short longitudinal slits
100 *c* inwardly of the rolled portions, and the
material bounded by said slits is bent back-
wardly when inwardly on the blank at 17
to reinforce said end portion. The knife
portions of the device are formed by tongues
105 struck upwardly from the body plate and
extending transversely between the rolled
portions 15, the spaces formed by striking
said tongues permitting passage of cut
material through the body plate. I prefer-
ably provide a set of three knife tongues 18,
110 two of said tongues being spaced apart and
aligned transversely of the body plate, while
the remaining tongue is disposed centrally

of the body plate and slightly in advance of the first named tongues, the width of said tongue being slightly greater than the distance between the two first named tongues. Experiment has demonstrated that this arrangement of the tongues procures a most easy cutting action of a bar of soap or the like which is slid upon the body plate, and procures an even flake or 10 ribbon of the cut material.

In forming the tongues, male and female dies *v* and *w* respectively are provided, the male die being provided with a punch projection *x*, while the female die is provided 15 with a recess *y* which receives the punch projection, the inner face of the recess *y* conforming to the knife bevel which it is desired to impart to the knife tongue and being hence disposed parallel to the body 20 plate engaging the face of the female die. Thus, referring particularly to Fig. 5, it is seen that as the tongue is formed by the dies, its free edge portion will be afforded a knife bevel, the metal of said free edge 25 portion being thus compressed as it is shaped, to harden the same and present a durable knife edge.

By the aforescribed general construction, an exceedingly simple and cheap, yet 30 durable and efficient cutting device has thus been provided which is particularly adapted for cutting or flaking soap into a washtub. In the use of the device, the operator stands over a tub, grasping the handle end of the 35 device with one hand, the channel 12 of

the other end of the device being engaged with the farther edge of the tub. The cake of soap is then reciprocated on the plate, being guided by the rolled portions 14 of the sides of the plate, and upon each reciprocation the soap will be cut over its entire area by the knife tongue. 40

What is claimed is:

1. A cutting device including a body blank provided with inwardly extending 45 slits adjacent one end, the side portions of the blank outwardly of the slits being bent back upon the blank to form a reinforced tongue, said reinforced tongue being bent to provide a channel for receiving the edge 50 of a support, and knife members carried by the body blank.

2. A cutting device comprising a body plate forming a slideway, an elongated U-shaped length of wire disposed thereon, 55 with its bight extended beyond one end portion of the body plate and its legs terminating short of the other end portion of the body plate, the side portions of the body plate being rolled about the legs of 60 said U-shaped length of wire, said other end portion of the body plate being bent to form a channel portion for receiving the upper edge of a support, and knife members carried by the body plate. 65

In testimony that I claim the foregoing I have hereunto set my hand at Milwaukee, in the county of Milwaukee and State of Wisconsin.

HENRY A. STAAB.
